UNITED STATES PATENT OFFICE.

ZACHARIAH P. LANDRUM, OF COLUMBUS, MISSISSIPPI.

IMPROVEMENT IN HORSE-POWERS.

Specification forming part of Letters Patent No. **136,075**, dated February 18, 1873.

To all whom it may concern:

Be it known that I, ZACHARIAH P. LANDRUM, of Columbus, in the county of Lowndes and State of Mississippi, have invented a new and useful Improvement in Horse-Power; and I do hereby declare the following to be a full, clear, and exact description of the same, reference being had to the accompanying drawing forming a part of this specification.

The invention relates to horse-powers adapted to use upon cotton-gins; and consists in the mode of combining the essential parts, substantially as hereinafter described and subsequently claimed.

In the drawing, Figure 1 is a side elevation. Fig. 2 is a top view.

A represents an upright frame, in which is journaled a vertical shaft, B. On this shaft is placed a drive-wheel, C, on whose periphery comes the strain of the gin or other machinery which is worked. D D are the sweeps, consisting of rigid rods of metal or wood rigidly fastened on the bars E E. From the drive-wheel C depend the hangers F F, consisting

of stout iron bars, in which are fastened the end of levers. These levers are intended to be perfectly rigid, and not to touch the shaft B. G H are right-angled bars connected with shaft B, and braced by a radial bar, I. At the end of bar H is attached the bar E, which rests upon, but is not attached to, a diametrical bar, K. These bars together form a supporting-frame, L.

This construction affords a very convenient and smoothly-working horse-power, which has been practically tested and received by the public with great favor.

Having thus described my invention, what I claim as new, and desire to secure by Letters Patent, is—

One or more levers, D, wheel C having hanger F and fulcrum-frame E G G I, combined with shaft B, as and for the purpose described.

Z. P. LANDRUM.
